UNITED STATES PATENT OFFICE.

GEORGE R. STEINHAUSER, OF ST. LOUIS, MISSOURI.

DESIGN FOR A LAMP.

SPECIFICATION forming part of Design No. 25,945, dated August 18, 1896.

Application filed June 22, 1896. Serial No. 596,548. Term of patent 3½ years.

To all whom it may concern:

Be it known that I, GEORGE R. STEINHAUSER, of the city of St. Louis, State of Missouri, have invented a new and original Design for 5 Lamps, of which the following is a full, clear, and exact description, reference being had to the accompanying drawings, forming a part hereof.

In the drawings, Figure 1 is a front elevation of a lamp embodying the features of my design. Fig. 2 is a horizontal sectional view on the line 2-2 of Fig. 1.

The leading feature of my design consists in the circular projection from the front side 15 of the reservoir of the lamp and the clock-dial upon the front surface of said projection

In the drawings, 5 is a hexagonal base, approximately in the center of which is a circular elevation 6. The elevation 6 is somewhat 20 smaller in diameter at its top than at its bottom, and resting upon the elevation 6 is a second projection 7, the bottom of which is somewhat smaller than the top of the elevation 6, and the top of said elevation 7 is somewhat smaller than its base. Standing upon the elevation 7 is a scantily-draped female figure 8. The feet 9 of the figure are undraped and rest upon the upper surface of the elevation 7. The robe or drapery 10 25 rounds the trunk and hips of the figure and is parted in front, exposing the lower part of the legs 11 and extends down back of the legs and rests upon the elevation 7. The arms 12 of the figure are bare and in an elevated position, with the hands 13 at the top and sides of the head 14. A pillar 15 rests

upon the top of the head 14 of the figure and between the hands 13. A cylindrical body 16 has an inverted-cone-shaped bottom 17, the lower end of which rests upon the pillar 15. 40 The cylinder 16 rests in a vertical position, and its upper end 18 is conical, and the burner 19 of the lamp rests upon the apex of the conical end 18. The chimney 20 is positioned upon the burner 19 and the lamp-shade 21 is 45 suspended from the top of said chimney by means of the hooks 22.

Attached to the front side of the cylinder 16 is a projection 23, which is circular when seen in elevation. At the front end of said 50 circular projection 23 is a bead 24, surrounding and extending outwardly therefrom. A second circular projection 25 extends forwardly from said projection 23, and the front end of said projection 25 is flat and in a vertical plane, and upon the face thereof appears the clock-dial 26 and the clock-hands 27. Upon the vertical outer surface of the cylinder 16 and in alinement with the clock-dial 26 and extending entirely around said reservoir from one side of said clock-dial to the 55 opposite side are the raised figures 28.

I claim—

The design for a lamp, substantially as herein shown and described. 65

In testimony whereof I affix my signature in presence of two witnesses.

GEORGE R. STEINHAUSER.

Witnesses:

S. G. WELLS,
MAUD GRIFFIN.
